UNITED STATES PATENT OFFICE.

JOSEPH A. ENO, OF NEWARK, NEW JERSEY.

RAILROAD-RAIL JOINT.

SPECIFICATION forming part of Letters Patent No. 276,792, dated May 1, 1883.

Application filed January 16, 1883. (No model.)

To all whom it may concern:

Be it known that I, JOSEPH A. ENO, of Newark, in the county of Essex and State of New Jersey, have invented certain new and useful Improvements in Railroad-Rail Joints; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved railroad-rail joint. Fig. 2 is a cross-section of the same, and Figs. 3 and 4 are detail views.

Similar letters of reference indicate corresponding parts in all the figures.

My invention has relation to railroad-rail joints, and it contemplates certain improvements upon the rail-joints for which Letters Patent No. 185,901 were granted to me January 2, 1877, as hereinafter more fully described and claimed.

In the accompanying drawings, the letter A represents a railroad-rail, the foot of which rests upon a chair, B. This chair consists of a metallic plate, the sides C of which are bent upward and curved downward at the edges D, forming beads E upon their upper surface. These beads may be smooth or corrugated, as shown in Figs. 3 and 4, and project into grooves, F, in the angular fish-plates G, which grooves may also be either smooth or corrugated. The fish-plates are fastened upon both sides of the rails, at the joint, by means of nutted bolts H, and are angular in cross-section. The lower flanges, I, of the fish-plates are turned downward and inward at their edges J, catching in under the bent edges D of

the chair in such a manner that when the upper flanges of the plates are drawn toward the rail by tightening the nuts K upon the bolts the edges will bite in under the edges of the chair, holding the rail ends and the chair firmly together. When the beads upon the chair and the grooves in the fish-plates are corrugated in such a manner that the corrugations will fit in between each other, all play endwise is also avoided, making the whole joint as rigid as if it were one solid piece.

It will be seen that by this construction the joint is easily put together and as easily separated, and that by drawing the nuts tight upon the bolts the joint clamps the ends of the rails immovably.

Having thus described my invention, I claim and desire to secure by Letters Patent of the United States—

1. The combination of the chair B, having upward-bent sides C, forming beads E, the edges D of which are bent outward and downward, angular fish-plates G, having downward and inward bent edges J, and nutted bolts H, substantially as and for the purpose shown and set forth.

2. In the above-described railroad-rail joint, the combination of the chair B, the sides C of which form beads E, with the fish-plates G, the lower downward and inward turned flanges, I, of which form grooves F, substantially as and for the purpose shown and set forth.

In testimony that I claim the foregoing as my own I have hereunto affixed my signature in presence of two witnesses.

JOSEPH A. ENO.
